United States Patent Office.

JONATHAN CARL, OF GRENADA, MISSISSIPPI, ASSIGNOR TO HIMSELF AND J. A. CARL, OF SAME PLACE.

Letters Patent No. 89,125, dated April 20, 1869.

IMPROVEMENT IN CHURN-DASHER.

The Schedule referred to in these Letters Patent and making part of the same.

To all whom it may concern:

Be it known that I, JONATHAN CARL, of Grenada, in the county of Yalabusha, and State of Mississippi, have invented a new and useful Improvement in Churns; and I do hereby declare the following to be a full and correct description of the same, reference being had to the accompanying drawings, making a part of this specification, and in which—

Figure 1 represents a vertical longitudinal section;

Figure 2, a plan view, partly in horizontal section on the plane line $x z$, fig. 1; and

Figure 3, a detached view of mode of connecting the stationary dashers.

In order that those skilled in the art may be enabled to use my invention, I subjoin the following explanation of its manner of construction and workings.

In fig. 1, A A A represent the side and bottom of the churn-box, or tub, which is constructed in the form of a parallelopipedon of boards arranged with the grain of the wood running horizontally, instead of perpendicularly, as is usually the case, with the corners mitred, and the whole firmly bound together by hoops N, of suitable material, at proper distances apart. The bottom of the churn is inserted before the sides are finally fastened, by being set in grooves prepared in the sides for that purpose.

C represents the dasher-shaft, in the lower end of which is an iron pivot, or shaft c, which goes through the bottom of the churn, and rests upon the bed-piece K, as represented in the drawings, fig. 1.

D D' represent the dashers of the churn, having a hole the size of the shaft C at their centres made to receive the same, and when in use, are kept in their proper place upon the shaft by means of the pins d d'. Holes may be made in the shaft, to keep the dashers at any desired elevation, in this manner.

E represents the breakers, fastened in each one of

the four angles of the churn, their edges converging towards the centre.

These have portions of their width e e cut out, in order to permit the dashers D D to play freely.

The breakers E are secured in position by horizontal bars a a; as shown thereby in fig. 3.

The machinery is propelled by a belt, F, running from the driving-wheel, or drum H, supported in the frame I I, to the head O' of the shaft C.

The drum, or driving-wheel is propelled by one or two cranks upon the shaft that supports the wheel in the frame, as seen at M, fig. 2.

G is a pulley, over which the belt runs, and which is arranged to move up or down, as may be desired, to tighten or loosen the belt, being kept in position by means of one or more pieces passing through it into the body of the churn.

Having thus described my invention,

What I claim as new, and for which I desire to secure Letters Patent, is—

1. The combination of the breakers E and movable dashers D, constructed and arranged as described.

2. The movable dashers D and breakers E, operating within the churn-box A, as set forth, in combination with the driving-apparatus H, F, and M, and the pulley G.

3. The removable breakers E, in combination with horizontal bars a, for securing them in position, as represented.

To the above specification of my improvement in churn and dashers, I have signed my hand this 18th day of August, A. D. 1868.

JONATHAN CARL.
